(57) **CLAIM**

The ornamental design for a support ring of switch as shown and described.

DESCRIPTION

1. Support ring of switch

1.1 Front

1.2 Side

1.3 Back

1.4 Perspective

2. Support ring of switch

2.1 Front

2.2 Side

2.3 Back

2.4 Perspective

Support ring of switch has elongated holes essentially in the center of each side, smaller elongated holes in each corner of the support ring of switch, four recesses on the outside of each side of the support ring of switch, one recess on each inner side of the support ring of switch, radiused sections in each corner of the inner side of the support ring of switch; further, the top side of the support ring of switch is essential flat, whereas the back side of the support ring of switch has four bars, each one being angled, where in the middle part of each angled bar is in the area of the respective recess on the inner side of the support ring of switch and the both side parts of the bar extend into the direction of the radiused section in each corner of the inner side of the support ring of switch.

1 Claim, 8 Drawing Sheets
